FREQUENCY DIVIDER AND DISCRIMINATOR CIRCUIT

Murray G. Crosby, Riverhead, N. Y., assignor to
Radio Corporation of America, a corporation of
Delaware

Application March 7, 1945, Serial No. 581,448

8 Claims. (Cl. 250—27)

1

My present invention relates generally to reception of angle modulated carrier waves, and more particularly to a combined frequency divider and discriminator circuit for frequency modulated (FM) carrier waves.

One of the important objects of my present invention is to provide an FM discriminator-rectifier network, wherein the discriminator circuits are normally tuned to frequencies so widely spaced apart that the resonance curves of the discriminator circuits do not overlap at any points thereof, there being employed balanced rectifiers in conjunction with the discriminator circuits to provide a modulation-representative signal.

Another important object of my invention is to provide a frequency divider of the oscillating converter and amplifier type, so adjusted that two tuned circuits thereof are off-tuned on opposite sides of respective carrier frequencies, whereby impression of an FM signal on the tuned circuits causes the amplitude of the oscillations in the two tuned circuits to be modulated in opposite directions, in association with a differential detector network for detecting the amplitude modulated oscillations.

Another object of my present invention is to provide a novel FM detection system which eliminates the need for an amplitude limiter, and which may be adjusted automatically to squelch noise in the absence of received FM signals.

Still another object of my invention is to add further utility to a frequency divider network of the type disclosed and claimed in my U. S. Patent No. 2,344,678, granted March 21, 1944.

Still other objects of this invention are to improve generally the efficiency and reliability of frequency divider networks in FM receivers, and more especially to provide frequency division networks functioning to discriminate and to provide an output of substantially uniform amplitude without the use of an amplitude limiter.

Still other features of my invention will best be understood by reference to the following description, taken in connection with the drawing, in which I have indicated diagrammatically a circuit organization whereby my invention may be carried into effect.

In the drawing:

Fig. 1 shows diagrammatically an embodiment of the invention;

Fig. 2 shows typical resonance curves of the discriminator circuits; and

Fig. 3 shows an alternative relation between the resonance curves of the discriminator circuits.

2

Referring now to the drawing, and particularly to Fig. 1 thereof, the frequency division system shown comprises tubes 4 and 20 whose circuits are substantially similar to those disclosed in my aforesaid patent. As explained in the said patent, frequency division networks are desirable for use in receivers of angle-modulated carrier waves, such as phase, or frequency, modulated carrier waves, and such frequency division networks have been disclosed in my U. S. Patent No. 2,064,106, granted December 15, 1936, as well as in my U. S. Patent No. 2,230,231, granted February 4, 1941. In the circuits of these patents, prior to demodulation of the frequency modulated carrier waves the latter are subjected to frequency division in such a manner that the frequency swing of the modulated carrier wave is reduced in the same proportion as the center frequency of the wave.

20 It will be understood that the frequency divider shown in Fig. 1 may be considered, for a specific utilization, as being located following the intermediate frequency (I. F.) amplifier network of an FM receiver of the superheterodyne type. 25 It is, however, to be clearly understood that the present invention is not limited to a superheterodyne receiver, nor to the specific frequency values given, nor to the specific frequency modulation. The generic expression "angle modulated" is intended to cover both phase modulation, frequency modulation and hybrid modulations which possess characteristics common to both phase and frequency modulation.

30 For the purpose of the present application, let it be assumed that the superheterodyne receiver is one employed in the present FM broadcast band of 40-50 megacycles (mc.), and that the first detector or converter reduces the center or carrier frequency of the modulated carrier waves to an I. F. value chosen from a range of 2 to 20 mc. In such case advantages are secured if a frequency division network is utilized to reduce the center frequency, say 4 mc., by a desired factor which is an integer. As explained in my 35 aforementioned patents, the frequency swing of the I. F. energy is simultaneously decreased by the same factor. If, for example, the center frequency is reduced by a factor of 4, then the frequency swing would be reduced by the same factor of 4. Since, in accordance with present standards of FM broadcasting, the maximum permissible frequency deviation in use in the 40-50 mc. band is 75 kilocycles (kc.) to either side of the center frequency, it will be seen that 40 reducing the center frequency by a factor of 4

will result in a reduction of the maximum overall frequency swing from 150 kc. to 37.5 kc.

Specifically considering the circuit of Fig. 1, let it be assumed that numeral 1 designates the usual intermediate frequency transformer coupled to the plate circuit of the last intermediate frequency amplifier tube. In that case each of the primary and secondary resonant circuits 2 and 3 would be tuned to the center frequency F . As stated before, and merely by way of specific illustration, F is assumed to have a value of 4 mc. As is well known, the center or carrier frequency is deviated at the transmitter in dependence upon the amplitude of the modulation signal, and the rate of overall frequency deviation is dependent upon the modulating frequencies themselves. The band width of transformer 1 will be in excess of the maximum frequency swing and will in the case assumed preferably be approximately 200 kc.

The numeral 4 designates the converter tube which may be of the 6SA7 type, although the invention is not restricted to this type of tube nor to a tube of the pentagrid type. Generally, the tube may comprise a cathode 5 and an output electrode, or plate, 6. Between the cathode 5 and plate 6 are arranged in sequential relation a signal input grid 7, a positive screen grid 8, a second signal, or oscillation, input electrode 9, a positive screen grid 10 and the usual suppressor grid 11. The cathode 5 is connected to ground through the customary biasing resistor 12 shunted by an intermediate frequency by-pass condenser. The low potential side of secondary circuit 3 is established at ground potential, while the opposite side is connected to the signal grid 7. The electrode 9 is connected through resistor 13 to the grounded end of biasing resistor 12. The functions of grids 7 and 9 may be interchanged, if desired.

The plate 6 is connected to the positive terminal +B of a direct current source through a resonant output circuit comprising a coil 14 shunted by condenser 15. The circuit 14, 15 is presently assumed to be tuned to a frequency

$$\frac{F}{n}$$

It will be understood that n may be any factor which is an integer. The signal modulated carrier voltage developed across circuit 14, 15 is transmitted through the condenser 16 which has a low impedance to the carrier voltage. As heretofore explained, it is desired to divide the center frequency of the modulated carrier waves and secure simultaneous proportional reduction of the frequency swing, which is taken as twice the frequency deviation. Hence, the effective frequency swing of the energy in circuit 14, 15 would be reduced n times. If the effective band pass width at transformer 1 was 200 kc., and n equalled 4 then, the pass band width at tuned circuit 14, 15 would be approximately 50 kc.

The frequency multiplier tube is designated by numeral 20, and it may be a tube of the pentode type such as is now known commercially as the 6SK7. The cathode 21 of this tube includes a self-biasing resistor 22 connected to ground and shunted by an appropriate bypass condenser. The input grid 23 is connected by the coupling condenser 24 to the high potential side of circuit 14, 15, the grid being connected to ground through the leak resistor 25. The plate 30 of tube 20 is connected by lead 31 and coupling condenser 32 to the grid 9. The plate 30 is, also, connected

to the high potential side of a resonant circuit comprising a coil 40 and a shunt condenser 41, the low potential side of this circuit being connected to the positive terminal +B of the direct current source.

Circuit 40, 41 is tuned to a frequency which is presently assumed to be equal to

$$(n \pm 1) \frac{F}{n}$$

In the specific illustration given, the resonant frequency of circuit 40, 41 would be either 3 mc. or 5 mc. The biasing resistor 22 is given a value such that, in the absence of input voltage to grid 23, direct current voltage developed across resistor 22 is sufficient to bias grid 23 close to plate current cut-off. It will now be realized that the resonant frequency voltage developed across the circuit 40, 41 is impressed upon the electrode 9 simultaneously with the impression of the frequency-modulated carrier wave energy of center frequency F upon grid 7.

The frequency modulated carrier wave voltages impressed on respective grids 7 and 9 are heterodyned by virtue of electron coupling, and produce the beat frequency voltage whose center frequency is

$$\frac{F}{n}$$

in circuit 14, 15. Hence, it will be seen that the output of the converter tube is tuned to the desired subharmonic frequency, and that this converter output voltage is fed to the input electrode 35 of a frequency multiplier tube. In the latter circuit the subharmonic frequency receives a multiplication of $n \pm 1$ times, and this multiplied output is then fed to the electrode 9 of the converter tube 4 so that the output of the converter 40 consists of the heterodyne beat between the center frequency F and the frequency of the voltage developed across circuit 40, 41. It will be seen that under these circumstances an oscillation will exist in circuit 14, 15 when the converter gain and 45 the multiplier gain exceed unity. The converter gain depends upon the strength of the signal applied from the input transformer 1. Hence, in the absence of signal energy at the input transformer 1 there will be no output voltage at circuit 14, 15 since there will be no oscillations produced through the multiplier tube. Tubes 4 and 26 cooperate with the associated tuned circuits to provide a re-entrant circuit i. e., a regenerative modulation circuit. The constants of the tubes 55 4 and 20 are chosen so that when the signal input level exceeds a predetermined amplitude then the re-entrant action becomes sufficient to sustain oscillation.

Additionally, the network may have its constants adjusted so when the signal input voltage is raised above the level required to start oscillations the output voltage does not appreciably increase. Accordingly, when used to divide the frequency, or phase, deviation in a frequency, or phase, modulation receiver, the division network 60 also permits the usual limiter stage employed prior to the detector to be dispensed with.

A further advantage of this type of frequency divider, when employed in a frequency, or phase, modulation receiver, is in the selective action thereof. Due to the resonant frequencies of the circuits employed in the regeneration circuit, there is a limited range of frequency F which will cause the system to oscillate and produce an output voltage. Thus, the receiver may be tuned

5

to the proper center frequency F so as to produce oscillations in the divider, and interfering signals which do not have the frequency F , but which come through the usual selective circuits, will be rejected.

A still further advantage which this division circuit has for use in frequency, or phase, modulation receivers is its threshold action. The latter can be utilized to eliminate noise from the receiver in the absence of signals. The usual frequency modulation receiver produces a roar of noise when there is no signal present. This is due to the fact that the limiter increases the gain of the receiver so as to amplify the noise to full volume. However, with the present type of frequency divider network, the gain of the receiver may be adjusted so that the threshold of the divider is just above the noise level. Hence, there will be no output voltage unless a signal is present which is stronger than, and overrides, the noise level. It will therefore, be appreciated that the present frequency division network improves the signal to noise ratio at the demodulator input circuit by virtue of the conjoint action of the division of the frequency swing of the frequency modulated carrier waves and the threshold action of the network itself. Furthermore, by virtue of the improved selectivity and the substantially constant output, distortion is greatly minimized.

In accordance with my present invention I utilize both tuned circuits 14, 15 and 40, 41 as discriminator input circuits. Instead of tuning these circuits to the respective frequencies

$$\frac{F}{n}$$

and

$$\frac{F}{n}(n \pm 1)$$

I tune them respectively to frequencies below and above said frequencies or vice versa. Assuming the specific illustrative examples given above, circuit 14, 15 may be tuned to a frequency less than 1 mc. by a predetermined amount, and circuit 40, 41 is in such case tuned to a frequency greater than 5 mc. (or 3 mc.) by a predetermined amount. As a result of such relatively opposite detuning of circuits 14, 15 and 40, 41 there is produced amplitude modulated carrier wave energy across each of the circuits.

Rectifiers 42 and 41 are shown as being of the diode type; it is to be understood that any other well known form of detector device may be utilized in place of the diode rectifiers. Anode 43 of diode 42 is coupled to the plate side of circuit 14, 15 through condenser 46. Cathode 44 of diode 42 is connected to ground through load resistors 46 and 50 arranged in series. I. F. bypass condensers 47 and 51 shunt respective resistors 46 and 50. Resistor 45 provides a direct current return path from anode 43 to the negative end of resistor 46. Resistor 52 is also a direct current return path and connects cathode 49 of diode 41 to ground. An I. F. choke of high impedance at the frequency of circuit 40, 41 may replace resistor 52. Condenser 48 couples the cathode end of resistor 52 to the plate side of circuit 40, 41. It will be obvious that condensers 46 and 48 function as direct current blocking condensers.

The modulation-representative voltage is taken off between the cathode end of resistor 46 and ground by leads 53. In other words, the rectified signal voltages across resistors 46 and 50 are

6

combined in differential or polarity opposing relation so as to provide the usual advantages of a balanced FM detector. The leads 53 may feed the modulation signal voltage to any desired and suitable amplifier which may be followed by an ultimate reproducer.

The functioning of the detector circuits will now be described, it being pointed out that Figs. 2 and 3 show curves illustrative of the invention. 10 In Fig. 2 I have shown the relation between the "amplitude vs. frequency" curves of circuits 14, 15 and 40, 41 for the condition where the normal frequency of the latter would be

$$\frac{F}{n}(n+1)$$

while in Fig. 3 the curves are shown for the case where circuit 40, 41 has a normal frequency of

$$\frac{F}{n}(n-1)$$

In Fig. 2 the input signal frequency is shown located by the vertical dotted line F at 4 mc. The output circuit 14, 15 is tuned, in accordance with my invention, to a frequency sufficiently less than 1 mc. to permit the frequency of 1 mc. to fall on a substantially linear portion of the upper flank of resonance curve a . In other words, if curve a represents the resonance curve of circuit 14, 15 for the off-tune condition, 25 the value

$$\frac{F}{n}$$

35 may be indicated to fall at point b of resonance curve a . The dotted line curve c shows what the resonance curve of circuit 14, 15 would be if it were tuned to the frequency

$$\frac{F}{n}$$

In the same way curve d illustrates the resonance curve of circuit 40, 41, and shows circuit 40, 41 to be tuned to a frequency somewhat 45 higher than the frequency

$$\frac{F}{n}(n+1)$$

Dotted line curve e shows what the resonance 50 curve of circuit 40, 41 would be if it were tuned to 5 mc. The frequency

$$\frac{F}{n}(n+1)$$

55 or 5 mc., falls at point g of the lower flank of resonance curve d . Here, again, point g should fall at a substantially linear portion of the lower flank of resonance curve d .

It is important to locate points b and g on 60 respective curves a and d so that the maximum frequency swings at circuits 14, 15 and 40, 41 can be accommodated. The maximum frequency swing at input circuit 1 has been assumed to be 150 kc. Under these conditions the maximum 65 frequency swing at circuit 14, 15 is 150 kc. divided by 4, which is 37.5 kc. Hence, point b should be located so that the maximum frequency swing of the I. F. energy at circuit 14, 15 will be 18.75 kc., above and 18.75 kc., below point b without going off the linear part of the resonance curve. At circuit 40, 41 the maximum frequency swing is 37.5 kc. multiplied by 5, or 187.5 kc. Therefore, point g is located on the resonance curve d , and the resonance curve d is chosen 70 accordingly, so that the maximum frequency

swing of the energy at circuit 40, 41 will be 93.75 kc., above and 93.75 kc. below point *g* without going off the linear part of the resonance curve.

The relations in Fig. 3 are similar, except that circuit 40, 41 is tuned to a frequency above 3 mc., or in excess of

$$\frac{F}{n}(n-1)$$

The frequency *F* of the input signals falls above the peak frequency of circuit 40, 41 in that case. However, the point *g'* on curve *d'* will be located as explained in connection with curve *d*. An examination of points *b* and *g* (or *g'*) reveals that operation along these points is productive of variable-amplitude carrier energy at respective circuits 14, 15 and 40, 41.

It can be seen from Figs. 2 and 3 that when the signal input energy instantaneously deviates higher in frequency, that is shifts above the value *F*, the energy developed at circuit 14, 15 is modulated towards a lower amplitude while the energy developed at circuit 40, 41 is concurrently modulated towards a higher amplitude. The reverse is, of course, true as the instantaneous signal input frequency deviates to a frequency less than *F*. In other words, Figs. 2 and 3 clearly show that as the instantaneous frequency of the signal input energy deviates below and above frequency *F* the amplitudes of signal energy at circuits 14, 15 and 40, 41 will correspondingly vary, but in opposite senses.

This is the familiar condition required for operation of a balanced FM detector. By rectifying the variable amplitude signal energy at each of circuits 14, 15 and 40, 41 by means of respective rectifiers 42 and 41, there is provided rectified signal voltage across each of load resistors 46 and 50. These output resistors 46 and 50 are connected so as to provide a differential modulation signal voltage which is representative of the amplitude modulations superimposed on the FM waves in the separate tuned circuits 14, 15 and 40, 41. Although in the foregoing description, the circuit 14, 15 has been described as detuned to a frequency below

$$\frac{F}{n}$$

and circuit 40, 41 has been described as detuned to a frequency above

$$\frac{F}{n}(n+1) \text{ or } \frac{F}{n}(n-1)$$

as the case may be, this action may be reversed in that circuit 14, 15 may be detuned to a frequency above

$$\frac{F}{n}$$

and circuit 40, 41 may be detuned to a frequency below

$$\frac{F}{n}(n \pm 1)$$

as will be apparent to those skilled in the art.

By a proper adjustment of the grid leak resistors and electrode voltages of tubes 4 and 20, the amplitude of the oscillations in the re-entrant circuit may be made independent of the amplitude of the FM signal over a range of signal inputs. This characteristic tends to give oscillator output of uniform amplitude despite amplitude modulation on the incoming FM signal, and, therefore, the circuit does not require an amplitude limiter. The system, of course, possesses the

various other characteristics described above and claimed in my aforesaid U. S. Patent No. 2,344,678. It will be particularly noted that although circuits 14, 15 and 40, 41 function as discriminator circuits, yet the resonance curves thereof do not overlap at any point and are in fact relatively widely spaced in the frequency spectrum.

While I have indicated and described a system for carrying my invention into effect, it will be apparent to one skilled in the art that my invention is by no means limited to the particular organization shown and described, but that many modifications may be made without departing from the scope of my invention.

What I claim is:

1. In combination with a pair of rectifiers having respective load resistors and a differential output voltage circuit common to said resistors, a first tuned circuit connected to one rectifier, a second tuned circuit connected to the second rectifier, a source of angle modulated carrier waves having a predetermined center frequency, said first tuned circuit being resonant to a first frequency less than a predetermined subharmonic frequency of said center frequency, said subharmonic frequency falling on the upper flank of the resonance curve of the first tuned circuit, said second tuned circuit being resonant to a second frequency in excess of a third frequency which differs from the source center frequency by said subharmonic frequency, said third frequency falling on the lower flank of the resonance curve of the second tuned circuit, frequency multiplying means coupling said first tuned circuit to said second tuned circuit, and means responsive to said source waves and frequency multiplied wave energy for developing in said first tuned circuit angle modulated waves whose center frequency is reduced to said subharmonic frequency value.

2. In a frequency modulation discriminator of the type comprising a pair of differentially connected rectifiers; the improvement comprising respective resonant input circuits for said rectifiers, a source of frequency modulated waves tuned to a predetermined frequency, one of the input circuits being tuned to a predetermined frequency difference from a desired subharmonic frequency of the source frequency, said subharmonic frequency being located on a flank of the resonance curve of said one input circuit, the second input circuit being tuned to a predetermined frequency difference in an opposite sense from a frequency multiple of the subharmonic frequency, said frequency multiple being located on the opposite flank of the resonance curve of the second tuned input circuit, and connections including said source and two input circuits in a closed re-entrant system.

3. In combination with a pair of diode rectifiers having respective load resistors and a differential output circuit common to said resistors, a first tuned circuit connected to one rectifier, a second tuned circuit connected to the second rectifier, a source of frequency modulated carrier waves having a predetermined carrier frequency, said first tuned circuit being resonant to a frequency less than a predetermined subharmonic frequency of said carrier frequency, said subharmonic frequency being located on the upper flank of the resonance curve of the first tuned circuit, said second tuned circuit being resonant to a second frequency in excess of a third frequency which differs from said carrier frequency by said subharmonic frequency, said third frequency being located on

the lower flank of the resonance curve of the second tuned circuit, a frequency multiplier coupling the first tuned circuit to said second tuned circuit, and means for developing in said first tuned circuit frequency modulated waves whose carrier frequency is reduced to said subharmonic frequency value.

4. In combination with a pair of differentially connected rectifiers, respective resonant input circuits for said rectifiers, a source of angle modulated carrier waves tuned to a predetermined carrier frequency, one of the input circuits being tuned a predetermined frequency difference from a desired subharmonic frequency of said carrier frequency, said subharmonic frequency being located on one flank of the resonance curve of said one input circuit, the second input circuit being tuned a predetermined frequency difference in an opposite sense from a frequency multiple of the subharmonic frequency, said frequency multiple falling on the opposite flank of the resonance curve of the second input circuit, and connections including said source and two input circuits in a closed system.

5. In a detector of frequency modulated carrier waves, a pair of oppositely connected diode rectifiers, respective resonant input circuits for the rectifiers, said input circuits being tuned to resonant frequencies widely separated to prevent overlapping of the resonance curves thereof, and means, responsive to said waves, for applying to said input circuits modulated waves whose center frequencies are sufficiently different from the said separated resonant frequencies to cause amplitude-variable wave energy to appear in each rectifier input circuit and the center frequency of the waves applied to each of said input circuits being located on respectively opposite flanks of said resonance curves.

6. In combination with a pair of detectors having respective load resistors and differential output voltage circuit common to said resistors, a first tuned circuit connected to one rectifier, a second tuned circuit connected to the second rectifier, a source of angle modulated carrier waves having a predetermined center frequency, a frequency divider having said first tuned circuit as its output circuit, said first tuned circuit being resonant to a frequency less than a predetermined subharmonic frequency of said center frequency, said subharmonic frequency falling on the upper flank of the resonance curve of said first tuned circuit, a frequency multiplier including said second tuned

circuit as its output circuit, said second tuned circuit being resonant to a frequency in excess of a frequency which differs from the source center frequency by said subharmonic frequency, said differing frequency being located on the lower flank of the resonance curve of the second tuned circuit, and means responsive to said source waves and frequency multiplied wave energy for developing in said first tuned circuit angle modulated waves whose center frequency is reduced to said subharmonic frequency value.

7. In a frequency modulation discriminator of the type comprising a pair of differentially connected rectifiers; the improvement comprising respective resonant input circuits for said rectifiers, a source of frequency modulated waves tuned to a predetermined frequency, a frequency divider including one of the input circuits tuned a predetermined frequency difference from a desired subharmonic frequency of the source frequency, said subharmonic frequency being located on one flank of the resonance curve of said one input circuit, a frequency multiplier including the second input circuit tuned a predetermined frequency difference in an opposite sense from the frequency multiple of the subharmonic frequency, said frequency multiple being located on the opposite flank of the resonance curve of the second input circuit, and connections including said source and two input circuits in a closed re-entrant system.

8. In combination, a pair of differentially connected detectors, respective input circuits for the detectors, said input circuits being tuned to spaced resonant frequencies to prevent overlapping of the resonance curves thereof, and means, responsive to angle modulated waves, for applying to said input circuits angle modulated waves whose center frequencies are substantially different from said spaced resonant frequencies and the center frequencies of the waves applied to the respective input circuits being located on respectively opposite flanks of said resonance curves.
